UNITED STATES PATENT OFFICE.

LOUIS GUICHARD, OF PARIS, FRANCE.

FUEL-FEED DEVICE.

Application filed December 27, 1923. Serial No. 683,072.

To all whom it may concern:

Be it known that I, LOUIS GUICHARD, of 1 Avenue Peterhof, Paris, France, have invented a Fuel-Feed Device, of which the 5 following is a full, clear, and exact description.

The present invention relates to fuel feeding devices in which use is made, for elevating a liquid of the partial vacuum existing 10 in a pipe line. This apparatus is mainly applicable to motor vehicles: it then serves to elevate the fuel contained in a tank arranged at any level for bringing it at a point situated at a higher level than the car- 15 buretor.

The apparatus forming the subject-matter of the invention is essentially characterized by the fact that it comprises, as movable parts ensuring its operation, only the usual 20 float and a tube-piston mounted, with some play, in the axis of the said float which determines the displacement of this tube-piston sometimes upwardly and sometimes downwardly, for producing, at suitable moments, the opening or the closing of the 25 various orifices provided for the working of the device. This arrangement, which is remarkably simple, allows therefore the doing away with all delicate parts capable 30 of getting out of order, such as levers, needle valves, springs, rocking valves, etc.

The accompanying drawing diagrammatically illustrates, in vertical section through the axis, a form of construction, given by 35 way of example, of the apparatus forming the subject-matter of the invention.

As shown in the drawing, the apparatus comprises a vessel 1 arranged in the feeder 2 to the upper wall of which it is secured. 40 On this wall is mounted, on the outer side, a cylinder 3 open at its lower part and on the head of which is secured a pipe 4 connected to a suitable point of the suction pipe of the engine (or, generally speaking, to a 45 closed space in which exists a sufficient partial vacuum); on the lower wall of the vessel 1 is secured another cylinder 5 arranged exactly in alignment with the cylinder 3.

In the wall of the upper cylinder 3 are 50 provided, at a level determined as indicated hereafter, one or more orifices 6 opening in the atmosphere; the said cylinder communicates through the conduit 7 with the interior of the vessel 1. The lower cylinder 5

is also perforated with a number of ori- 55 fices 8.

In the vessel 1 can move a float 9 perforated, according to its axis with a hole 10 in which fits, so as to be capable of freely moving, a tube piston 11 provided throughout its height with large openings, as illustrated at 12 in the drawing. On this tube are secured, at the upper part, a piston 13 and, at the lower part, a slide valve or ring 14; both parts 13 and 14 move with slight 60 friction, the piston 13 in the cylinder 3, the slide valve or ring 14 in the cylinder 5.

It is to be understood that the piston 13 and the slide valve or ring 14 could be done away with the tube 11 (which must, of 70 course, in this case, be closed at its upper end) then constituting the piston in the upper cylinder.

On the tube 11, at suitably determined points of its length, are secured two abutments 15 and 16 arranged on either side of the float.

A pipe 17 feeds, in the vessel of the apparatus, the liquid to be elevated which comes from a tank situated at any point; finally, 80 from the bottom of the feeder 2 extends a pipe 18 leading to the apparatus which is to be fed.

The operation of the device which has 85 just been described is as follows:

Supposing the system is in the position illustrated in the figure: the float 9 rests on the lower abutment 16 of the tube 11; the slide valve 14 closes the orifices 8, whilst the piston 13 uncovers the orifice through which 90 the channel 7 opens in the cylinder 3, obturating at the same time the orifice 6 communicating with the atmosphere. In this position the interior of the vessel 1 communicates, through the channel 7 and pipe 4, 95 with the closed space in which exists the partial vacuum. Under, the action of this partial vacuum, the liquid is sucked in the tank through the pipe 17 and it flows into the vessel 1. In proportion to the arrival 100 of the liquid in the vessel 1, the float rises until it comes in contact with the upper abutment 15.

During all this phase of the operation, the upper piston 13 is in equilibrium as far as 105 the pressure is concerned, since its two faces are both subjected to partial vacuum.

The liquid continuing to flow into the ves-

sel 1, the float continues to rise and, in its movement, it pushes the tube 11, by acting on the upper abutment 15, until the orifice 6 is uncovered. At the same moment the upper orifice of the channel 7 is obturated by the piston 13, the position of the said orifices being determined in such a manner that, when the lower edge of the piston comes level with the lower edge of the orifice 6, the upper edge of the said piston comes level with or has just passed by the upper edge of the orifice of the channel 7. Consequently, when the opening of the orifice 6 begins, the channel 7 is closed. The interior of the vessel 1 being then at atmospheric pressure, the liquid in the tank ceases to be sucked through the pipe 17 and the flow of this liquid into the vessel 1 is interrupted.

At this moment, the equilibrium of pressure to which the piston 13 was subjected, is broken, as its lower face communicates with the atmosphere, whilst its upper face remains subjected to the partial vacuum existing in the pipe 4. It results therefrom that the tube-piston is rapidly drawn upwardly and that the slide valve 14 uncovers the orifices 8; the liquid contained in the vessel 1 then flows out into the feeder 2, by passing through the orifices 12 of the tube 11.

The float 9 descends, of course, with the level of the liquid until it rests on the lower abutment 16 and it remains in this position a certain time, although the level of the liquid continues to lower in the vessel, because the tube-piston is retained by the partial vacuum acting upon its upper face. When, the liquid continuing to flow out through the orifices 8, the weight of the float succeeds in overcoming the partial vacuum exerted on the upper face of the piston 13, the float descends, drawing along the tube 11 with it. As soon as, during this movement, the orifice 6 closed and the orifice of the channel 7 is open, the equilibrium of pressure is suddenly re-established on both faces of the upper piston 13: the tube descends suddenly under the action of the weight of the float and the slide valve 14 obturates the orifices 8. From this moment, the movable parts are again in the position illustrated in the drawing, the vessel 1 is again in communication with the pipe 4 and the suction of the liquid through the pipe 17 recommences.

It will be noted that the arrangement of this apparatus is such that the orifices 6 and 7 can never be simultaneously open; consequently, no loss of charge is to be feared in the operation of the system and, in the application of the apparatus to internal combustion engines, the fuel supplied to the feeder is ensured for all the speeds of the engine. The opening and closing of the various orifices are thoroughly and instantaneously ef-

fected. Finally, the security of the operation is increased owing to the fact that the apparatus does not comprise any part capable of failing or of getting out of order.

Claims:

1. In a fuel feeding device, a container, a pipe for feeding fuel into said container, a conduit adapted to be connected to a source of vacuum for creating vacuum in the container, a vertically movable element arranged partly in the container and having spaced stops, a float slidably mounted on said element and movable between said stops, a piston fixed to said element, a cylinder associated with the container and having a passageway for placing the interior of the container in communication with said conduit, said passageway opening into the cylinder at one elevation, a port in the cylinder arranged at a different elevation and adapted to place the interior of the container in communication with the atmosphere, said piston being movably mounted in the cylinder and arranged to control said port and passageway.

2. A fuel feeding device as claimed in claim 1 in which the conduit is connected to the top of the cylinder and communicates with the upper end of the interior of the cylinder.

3. A fuel feeding device as claimed in claim 1 including a second container to receive the fuel from the first container, and means controlled by the vertically movable element for feeding the fuel from the first to the second container.

4. A fuel feeding device as claimed in claim 1 in which the vertically movable element consists of a tube.

5. A fuel feeding device as claimed in claim 1 in which the vertically movable element consists of a perforated tube for feeding fuel from the container.

6. A fuel feeding device as claimed in claim 1 including a second container, means for conveying fuel from the first to the second container, and a tubular part controlled by the vertically movable element for controlling the last mentioned means.

7. A fuel feeding device including an outer container adapted to receive fuel to be fed to a carburetor, an inner container having top and bottom cylinders, ports in the bottom cylinder for passing fuel from the inner container to the outer container, a pipe connected to the upper end of the upper cylinder and adapted to be connected to an engine for creating suction in the upper cylinder, a passageway placing the upper portion of the upper cylinder in communication with the inner container, a port in the lower portion of the upper cylinder for placing the interior of the inner container in communication with the atmosphere, a pipe for feeding fuel into the inner con-

tainer from a storage tank, a vertically movable perforated tube arranged partially within the inner container and having its ends extending into said cylinders, a piston 5 on the upper end of the tube for controlling the port and passage way in the upper cylinder, a sleeve on the lower end of the tube for controlling the ports in the lower cylinder, spaced stops arranged on the tube, and a float slidably mounted on said tube between said stops.

The foregoing specification of my "improved exhauster" signed by me this 7th day of December, 1923.

LOUIS GUICHARD.
